AUTOMATIC RESET CIRCUIT BREAKER

William H. Frank, Detroit, Mich., assignor to
 Bulldog Electric Products Company, Detroit,
 Mich., a corporation of West Virginia

Application April 21, 1933, Serial No. 667,151

13 Claims. (Cl. 200—116)

This application relates to automatically resetting circuit breakers and can best be understood with reference to my copending application Serial No. 667,149, filed April 21, 1933.

In the above identified applications there has been disclosed an automatically resetting circuit breaker which may operate in such a fashion that a continuous cycle of overload release and automatic reset will occur so long as there exists on the controlled circuit an overload condition. The circuit breaker of that application includes a spring motor which continuously functions to release and reset the breaker, and which therefore is apt to run down. It is therefore considered desirable to provide for such a motor, a means for maintaining the spring motor continuously wound, and/or b means whereby the condition of the spring will be brought to the attention of the householder, when the spring has run down to a dangerous point, and the inventions of this application aim to provide such means a and b.

The means b is so constructed that it operates, when the spring has run down, to leave the breaker in the open circuit position. That is to say, the spring will always be of sufficient strength to open the circuit, on overload or short circuit, for safety's sake, but if its strength runs down, it will not operate to close the circuit after its last circuit opening operation.

The invention further aims to provide means automatically operable to reveal the condition of the breaker controlled circuit, the means having selectively visible indicia, such as "On", "Wind" and "Off".

Further objects will presently appear upon reference to the following detailed description of preferred embodiments of the inventions, these embodiments being shown in the appended drawings. In these drawings—

Fig. 1 is a top plan view of an automatically resetting circuit breaker provided with an automatic spring rewinding device.

Fig. 2 is a section as if on line 2—2 of Fig. 1.

Fig. 3 is a section as if on line 3—3 of Fig. 1.

Fig. 4 shows a spring detent and is a section as if on line 4—4 of Figures 1 and 5.

Fig. 5 is an end elevational section of the device as if from the left of Fig. 1.

Fig. 6 is a right end view of the same.

Fig. 7 is an elevational section of the same as if on line 7—7 of Fig. 5.

Fig. 8 is a similar view as if on line 8—8 of Fig. 6.

Fig. 9 is a view like that of Fig. 2 but with the parts shown in "Overload release" position.

Fig. 10 is a view like that of Fig. 9 but with the parts shown in an "Off" position, due to manual control operation.

Fig. 11 is a view like that of Fig. 9 but with the parts shown in an "Off" position produced by 5 manual reset latching.

Fig. 12 is a section on line 12—12, Fig. 14 and shows a breaker equipped with means for insuring the breaker being left in open circuit position, when the operating spring has run down, the 10 parts being shown in closed circuit position.

Fig. 13 is a view of the device of Fig. 12, parts being shown in open circuit position, and is a section on line 13—13, Fig. 14.

Fig. 14 is a cut away end view of the device. 15

Fig. 15 shows a modified form of detail, providing an indicator.

The breaker of Figures 1 to 11

The automatically resetting breaker of these 20 figures is characterized by the fact that the thermal element moves in a direction normal to the operating shaft, and functions thru a separate release element to release the shaft for trip and reset of the breaker. The breaker parts are 25 mounted upon a base 71 of insulating material and are enclosed within a cover 71a, also of insulating material, the cover having slots through which projects the three manually engageable parts of the breaker, namely; the winding drum 30 72, the manual control handle 74, and the manual reset latch handle 75. The breaker parts will now be described specifically.

Pivotedly mounted on an axle pin 76, to and between the upstanding fixed framed plates 77, is 35 the breaker contact arm 78, the arm having a contact 79 for engaging the fixed contact 80 of the breaker. As shown, the line is connected to the arm, but it may well be connected to the contact 80, in which case the arm would be connected to 40 the load thru the thermal element. Pivotedly connected by an axle pin 81 to two upstanding parts of the breaker contact arm 78 are connecting rod links 82 which at their upper ends are connected to a crank 83 formed on the breaker operating shaft 84, the latter being trunnioned in aligned bearing holes of the upstanding framed plates 77. It is observed that rotation of the operating shaft 84 operates, through the medium of the crank 83 and the connecting rod links 82, 45 50 to move the contact arm 78 to and from contact making and breaking position, and the crank and links serve as a toggle clamp for the arm, when in "On" position.

One end of the operating shaft is bent perpen- 55

dicularly from the axis of the shaft to provide a holding crank 85 adapted to be held by one or another of the stops actuated by the thermal element referenced generally "T". The latter is connected at one end, by a lead, to contact 80, and at the other, to the load.

The "On" holding stop, that is to say, the stop which holds the holding crank 85 in the "On" position, Figs. 1 to 8, is referenced 86 and is in the nature of a lug provided on a plate 87 whose end is connected to the bimetallic thermal element "T" so as to be reciprocated, normal to the shaft, by the thermal element, which warps normal to the shaft, the thermal element including relatively electrically and mechanically connected bimetallic strips 88 insulated from the plate 87 by an insulating strip 89, it being observed that the connection between the thermal element and the plate 87 includes a pivot 89a, which permits relative movement of the thermal element and the plate. The other stop, that is to say, the stop which holds the crank 85 in the "Off" position, Figs. 9 to 10, is referenced 90, and is also in the nature of a lug provided on plate 87. The stops 86 and 90 are relatively so spaced and so proportioned that when the holding crank is in the "On" position, the end of the crank will engage the lower right hand corner of the "On" stop 86, whereas when the crank is in the "Off" position, the end of the latter will engage the upper left hand corner of the stop 90.

The plate 87 is fixed to the upper end of a support 92 mounted on a bracket 92a in turn positioned on a block of insulating material 93, disposed in a depression in the upper surface of the base and mounted in key and groove runways therein and so proportioned as to be able to slide in such depression in a direction normal to the axis of the operating shaft 84. This block also supports the thermal element "T".

For manually sliding the block 93 in its depression, there is provided an actuating device whose handle has been previously referred to as a manual control handle 74. This handle is journaled in the base on the end of a stub shaft 94, and is pivotally connected at 95 to a bracket projecting upwardly from the block 93, and it will be observed that movement of the actuating handle 74 slides the block 93 in its depression. For latching the block 93 in the "On" position of Fig. 12, or in the "Off" position of Fig. 10, there is provided a spring 97 (Fig. 10) adapted to engage one or another of a pair of notches 98, formed in the lower surface of the block.

On the end of the operating shaft 84 opposite that end thereof, which is formed as a holding crank 85, is a drum, previously referenced 72, and containing a clock spring 100, wound upon the end of the operating shaft and having one end fixed to the shaft and the other end fixed to the drum 101. This spring tends to rotate the operating shaft clockwise (Fig. 2) and its influence is opposed by the stops 86 and 90, previously mentioned.

For winding the spring, the operator may manually rotate the drum, which is rotatably journaled on the shaft and is held against reverse rotation by a ratchet wheel 103 fixed to the drum and disposed between a frame plate 11 and the drum, as indicated in Fig. 1. A clock work pawl 104 cooperates with the ratchet to prevent movement of the drum in the counterclockwise direction as the drum is being rotated clockwise to wind the spring, it being observed that the drum can be wound by moving it with the thumb.

Automatically operating spring rewinding means are also provided and these will presently be described.

In order to provide a manual reset latch which maintains the breaker open and prevents the breaker from being reset in any manner except manually, there is slidably mounted on one of the upstanding frame plates 11 a plate 107 guided on the upstanding frame plate through the medium of the slots 108 receiving pins 109 projecting from the spring. The latching plate is formed with an extension 111 adapted to be moved with the plate to underlie and project beyond the "Off" stop 90, and when so moved, to prevent rotation of the holding crank 85 from the "Off" position to the "On" position. The spring 112 cooperates with notches 113 in the lower edge of the plate 107 to define positions of the latter.

The operations of the breaker per se, apart from the automatic rewind means to be described, will now be described in complete detail. Assume the parts to be in "On" position. At this time the holding crank 85 engages and is disposed under the "On" stop 86, and the operating shaft and its associated parts are held in the "On" position, with the contact arm 78 in a horizontal position, so that contact 79 engages contact 80, the parts being held against the influence of the spring 100 which tends to rotate the operating shaft clockwise. It is observed that the thermal element occupies such a position on normal load that the stop 86 is directly in the path of holding crank 85.

Upon the arising of an overload, the thermal element "T" will warp normal to the operating shaft 84, that is to say, to the left of Fig. 2, sufficiently to move stop 86 out of the path of the holding crank 85. The spring 100 consequently rotates the parts clockwise with an extremely rapid movement. Such rotation causes an upward pull on the connecting rod links 82 and pivots contact arm 78 to the position of Fig. 13 from the position of Fig. 12; that is to say, it opens the circuit. When thermal element "T" warped to the left of Fig. 2, it placed stop 90 in the path of crank 85. Consequently, the crank rotates on overload but one-half turn, and is engaged by the stop 90, to restrain further rotation of the parts.

When the circuit has been opened sufficiently long for the thermal element "T" to cool and warp back to its original position, the stop 90 will move towards the right, out of the path of crank 85, and the latter will be released. Accordingly, the operating shaft will be free to rotate and the spring 100 will rotate the shaft another half-turn clockwise to close the circuit and to bring contact arm 78 once more under and against stop 86, which in in the meantime had moved with plate 87 to the right of Fig. 9.

If the overload still is on the line, this cycle of operations will be repeated, and will continue so long as the overload is in existence or until the operator manually opens the circuit breaker. It will consequently be seen that the circuit breaker automatically resets itself after having been opened on overload.

For manual control operations, the actuating handle 74 is utilized. If the breaker is to be moved from the "On" position, Fig. 2 to the "Off" position, Fig. 10, the handle 74 is moved to the left, Fig. 2, to the position of Fig. 10. Such movement of the handle causes the block 93 to slide to the left and this movement, carrying the thermal element "T" and the plate 87

with the block, takes the stop 86 out of the path of the crank 85 and places the stop 90 in the path of the crank 85. The spring 100 rotates the operating shaft to "Off" position. To restore the parts to "On" position, the actuating handle is moved back to the position of Fig. 2 which serves to move stop 90 away from crank 85, freeing the latter and the shaft for movement by the spring 100, which then rotates the 10 shaft until the crank 85 is engaged by the stop 86, which had moved into the path of the crank.

In the event it is desired to latch the breaker in the "Off" position, the manual reset latch handle 75 is moved from the position of Fig. 2 15 to the position of Fig. 11. Such movement of the handle, and obviously of the plate 107, projects the part 111 into a position directly into the path of crank 85. The manual switching handle 74 is then moved to "Off" position and 20 crank 85 rotates, and is ultimately held in "Off" position by part 111. Reset may be accomplished only manually, by moving latch back to "On" position manually.

25 *The automatic rewinding means: Figs. 1-11*

The automatic rewinding means disclosed in this application and which per se represents part of the novelty that this application possesses over the prior application above referred to, includes 30 a solenoid which is automatically energized whenever the contact arm 78 is moved to "Off" position by the spring motor. The solenoid circuit is in parallel with the contact arm and thermal element circuit and includes a pair of contacts 35 which are caused to engage by movement of the contact arm to an open circuit position, the solenoid circuit contacts being in series with the solenoid.

The solenoid operates a plunger which is connected to the drum of the spring motor thru suitable gearing and the operation is such that whenever the contact arm is moved to "Off" position, the solenoid is energized and the drum is rotated for rewinding the spring. A coil 45 spring on the plunger returns the solenoid plunger to its original position when the solenoid becomes de-energized due to return of the contact arm from "Off" position to "On" position.

The automatic rewinding mechanism will now 50 be described specifically.

Suitably mounted on the base 71 is a solenoid 120 electrically connected to the line side of the contact arm 78 by a lead 121 and electrically connected to a binding post 122 by a conductor 55 123. From this binding post there extends a conductor 124 which leads to an anchoring screw 125, and anchored to this screw is a leaf spring 126 bearing on its upper surface a contact 127, and on its lower surface a striker part 128, the latter being insulated from the leaf spring 126 by insulation at 129. The striker part lies directly over the contact arm 78 and is adapted to be engaged by the contact arm when the latter moves to "Off" position. When the striker arm 60 is engaged by the contact arm, the leaf spring 126 moves upwardly from the position of Fig. 7, so that contact 127 thereof, engages a contact 131 fixedly mounted and electrically connected to an anchoring screw 132. This screw is connected by a conductor 133 to a binding post 134, which in turn is connected by a lead 135, Fig. 2 70 to that binding post 136 of the thermal element "T" to which the load conductor, Fig. 1, is connected.

75 It will be seen that when the contact arm 78

moves upwardly Fig. 7, it will close an electrical circuit from the line conductor to the load conductor through the solenoid 120, to energize the latter.

It is observed that binding post 134 may be 5 connected directly to the other side of the line, in which case the solenoid will be connected directly across the line, shunting the load, when contact arm 78 moves upwardly and causes contacts 127-131 to engage.

10 It is further observed, that even when the solenoid is connected in series with the load, by connecting binding post 134 to the thermal element "T", it is so connected only upon the occurrence of an overload or short circuit. Accordingly, since the overload or short circuit has the effect of reducing the load resistance, even in such a case, the solenoid will receive full line voltage, as is of course true of the construction wherein the solenoid binding post 134 is connected to the other side of the line.

15 Further, it is contemplated to connect the solenoid to the load, and use it and its contacts, not only for rewinding, as here disclosed, but also as the solenoid of my application Serial No. 667,150, 25 filed April 21, 1933, wherein a solenoid, in series with the load, is used for controlling the manual resetting of the circuit breaker. Therefore, it can be said that there is here disclosed, on the principle of incorporation by reference to that application, a single solenoid used for rewinding and for controlling breaker reset.

20 When the solenoid is energized, it moves its plunger 140 to the right of Fig. 2 against the influence of the plunger spring 141 which bears 35 against a plate 142 of the solenoid and a pin 143 of the plunger. The remote end of the plunger is in the nature of a flat strip provided with rack teeth 145 on its upper surface, and having a slot 146 guiding the plunger on a pin 147 fixed to a 40 frame part 148. The rack teeth 145 of the plunger engage a pinion gear 147a rotatably journaled on a jack shaft 149 journaled in frame parts 148 and 150. Also journaled on the jack shaft and suitably fixed to pinion gear 147a is a 45 crank 151 whose spring detent 152 is in engagement with the teeth of a ratchet 153 keyed to the jack shaft, the connection between the pinion gear 147 and the jack shaft being a uni-directional one, so that rotation of the pinion 147a 50 in one direction, counterclockwise, Fig. 2, rotates the jack shaft counterclockwise, whereas rotation of the pinion 147a clockwise, Fig. 2, does not rotate the jack shaft clockwise. Also keyed to the jack shaft 149 is a large gear 154 which 55 meshes with a small gear 155, journaled on the end of the operating shaft 84, and fixed to the drum 72 so that the drum and the small gear 155 rotate in unison. The connection between the small gear and the drum may be effected in 60 any suitable manner, as for example, by a rivet or pin passed through a wall of the drum and the plate of the gear 155, such means not being shown, since it is well within the purview of the ordinary skilled mechanic.

65 It is observed at this time that the foregoing parts provide such an operative connection between the plunger and the drum that a slight but rapid movement of the plunger is magnified into a much greater but slower circumferential movement of the drum, this being desirable in order to provide sufficient and properly timed rewinding movement of the drum.

70 The connection between the pinion gear 147a and the shaft 149 operates in such a manner that 75

return of the plunger due to de-energization of the solenoid 120 and due to the influence of the spring 141, does not rotate jack shaft 149 and gears 154, 155 in a direction reverse from that which they attain when the solenoid is energized and the parts move for drum spring winding. This type of connection is desirable since it gives a one way rotation to the drum 72, regardless of the direction of movement of the solenoid 10 plunger.

The operation of the parts will readily be observed from the foregoing. Whenever the drum spring 100 causes the operating shaft 84 to rotate clockwise, Fig. 2, with a consequent unwinding of the drum spring, the solenoid is immediately energized to rewind the spring and restore it to its original condition, this operation, however, not affecting the operating shaft 84, or the circuit closing or opening parts.

20 It is noted that where the solenoid is connected to shunt the load, as previously described, it remains in circuit all the while the breaker is open, even though it had completed its function of re-winding the spring long before the thermal element returns to close the breaker.

The wind demand latch and indicator:

Figs. 12 to 15

In these figures, there is shown an auxiliary 30 which has been disclosed in connection with the circuit breaker of Figs. 1 to 11 of this application and which is intended to be used either as an addition to a circuit breaker equipped with an automatic rewinding device or as an auxiliary for a 35 circuit breaker not so equipped. The functions of the wind demand latch and indicator may be briefly described as follows:

strictly described as follows:

In the event the spring motor becomes unwound, or otherwise weakened to such an extent that it can no longer function satisfactorily to rotate the operating shaft to and from contact making and breaking positions, the contact parts will be so disposed that they will remain in an open circuit position, once they are moved to such a position. While this may cause some inconvenience to the householder, it will at least not endanger the apparatus or circuit which is to be protected by the circuit protective device. Otherwise, the parts might be left in a closed circuit position, with insufficient power in the spring motor to move them out of this position when an overload occurs.

Accordingly, there is provided and disclosed in these figures, a wind demand latch which latches the parts in open circuit position whenever the condition of the spring motor is such that rewinding of the same is demanded.

The provision of such a device, while in its own right desirable, might be considered objectionable if the circuit breaker were left in an open circuit position and the householder not told why the circuit breaker does not function. For this reason, there is included with the wind demand latch an indicating device which is automatically operated to indicate that the open circuit condition is due to the fact that the spring motor needs rewinding.

The foregoing parts will now be described specifically with particular reference to Figs. 12 to 14.
70 These figures show many parts which are identical with the correspondingly referenced parts of Figs. 1 to 11 inclusive. For example, these figures show a base 71 closed by a cover 71a through which projects a winding drum 72, a manual switching handle 74, and a manual "Off"

latch handle 75. An axle pin 76, mounted between frame plates 77, journals a breaker contact arm 78 having a contact 79 adapted to engage a fixed contact 80, and an axle pin 81 on the arm journals connecting rod links 82 which connect the contact arm to a crank 83 of an operating shaft 84, the latter having a holding crank 85 on its end. For holding the crank, there is provided an "On" stop 86 formed as a lug on plate 87 in turn connected to the thermal element, the latter including bimetallic strips 88 insulated from the plate 87 by insulation 89 and connected to the plate by a pivot 89a, and there is also provided on the plate 87, an "Off" stop 90.

Plate 87 is mounted on a slide block 93, actuated by the handle 74.

Other parts of the breaker which are like corresponding parts of the breaker of Figs. 1 to 11 are not mentioned specifically, it being understood that they are shown and described in connection with the breaker of Figs. 1 to 11.

The wind demand latch per se will now be described specifically.

Passing through a bracket 170 secured to the cover 71a and disposed parallel to the operating shaft 84 is an axle pin 171, on one of whose ends is keyed a bell crank 172 and on the other of whose ends is keyed a pawl 173. One end of the bell crank is connected at 174 to a coiled tension spring 175 which in turn is connected through a 30 spring tensioning screw at 176 to an extension 177 formed on bracket 170. The pawl 173 is in the path of rotation of the holding crank 85 and co-operates with such crank as follows:

Whenever the crank 85 is rotated from "On" position towards "Off" position, that is to say, clockwise, Fig. 12, the crank will engage pawl 173. It will pass by the pawl if the strength of the spring in drum 12, that is to say, the spring that rotates the operating shaft on which the holding crank 85 is formed, is greater than the strength of spring 175. If such be the case, the crank 85 in passing from "On" to "Off" position will do nothing more than kick the pawl 173 and rotate the bell crank 172 counter-clockwise against the influence of the spring 175 until the crank 85 passes by the pawl, after which the pawl 173 and the bell crank 172 will return to their normal position, Fig. 12.

If, however, the strength of the operating shaft 50 spring in drum 72 is not greater than the strength of spring 175, as for example when the operating spring has run down and needs rewinding, the holding crank will be prevented from reaching stop 90 by the pawl 173, as seen in Fig. 13, the 55 crank assuming a rest position somewhere between its "On" position and its full "Off" position. The crank, in the position of Fig. 13, has moved far enough to place the contact arm 78 in an "Off" position for circuit rupturing but is 60 nevertheless held from reaching its full "Off" position by the pawl.

With the holding crank so positioned, automatic resetting after overload release cannot be effected merely by a return of the thermal element and by a reciprocating movement of plate 81, because, regardless of such movement, pawl 173, as influenced by its spring 175, holds the crank 85 in the position of Fig. 13. In order to accomplish reset, it therefore becomes necessary for the householder to re-wind the spring in drum 72 sufficiently to cause the latter to overcome the strength of spring 175. When this is accomplished, the pawl 173 will release the crank 85 and will permit the latter to assume its full 75

"Off" position, from where it can be rotated by the spring to "On" position.

It will thus be seen that Figs. 12 to 14 show a device which maintains the part in open circuit position and prevents them from returning to closed circuit position whenever the spring in drum 72 needs rewinding.

The device of Figs. 12-14 may also be used as a means to limit the number of cycles of operations of the breaker, it being observed that the number of cycles of breaker release and automatic reset is determinable by the relative strengths and tensions of springs 100 and 175. The latter is adjustable and permits variation of the number of cycles permitted. The last cycle always will not be completed, terminating in a breaker release, without an automatic reset until the spring is rewound.

Further, the holding means can be provided to engage the crank on its path of movement between "Off" and "On", as well as between "On" and "Off", and either manner of relating the holding means to the crank may be used, as desired.

25 The indicating means, which is automatically operated to indicate the reason for the parts being maintained in the open circuit position, is in the nature of an indicator plate 180 formed on one of the arms of the bell crank 172, this plate being adapted to underlie and align with an opening 181 in the cover of the device so as to be visible through the opening 181. It will be observed that whenever the parts assume the rest position of Fig. 13, with the holding crank 35 85 held by the pawl 173, the legend "Wind" is presented to the operator and calls his attention to the necessity for rewinding the spring in drum 72.

40 The wind demand latch described in the foregoing might well be considered as a means for limiting the number of cycles of release and reset that may occur, since it will so function.

In Fig. 15 there is disclosed an indicating means having three indicator positions, "On", 45 "Wind" and "Off". The pawl 173 is replaced by a differently shaped pawl 273, and the plate 180 is replaced by a differently formed plate 280, having "On", "Wind" and "Off" marked thereon, as indicated. The other parts are the same, 50 and the device operates as follows: The parts, as indicated, are in the "On" position, with the "On" part of plate 280 under the window 181. When the crank 85 rotates clockwise, on overload, it will engage pawl 273 and move it counterclockwise. If the motor spring is weaker than 55 the spring 175, the plate 280 will move only halfway, to present "Wind" to the window, and the parts will remain held in open circuit position. If the motor spring is stronger than spring 175, 60 as is normally the case, the plate 280 will move all the way, to present "Off" to the window. This is the normal operation.

It is observed that "Off" will show when 65 crank 85 is held by stop 90. When it is thereafter released by stop 90, it will release pawl 273, and the indicator will be moved by its spring 175 to show "On".

It is also observed that the indicator plate 280 70 may be in the nature of a contact for closing an audible or illuminated indicator circuit, thus controlled by plate 280 and therefore, by the condition of the breaker itself.

Auxiliaries

75 It is at present contemplated to combine with

the devices shown in this application, and the combinations effected through the use of these devices, certain auxiliaries which are not here disclosed but which are disclosed in detail in certain copending applications which are being filed 5 simultaneously herewith.

For example, in application Serial No. 667,149, filed April 21, 1933, there are disclosed in Figs 1 to 10 and 11 to 18, two different forms of circuit breakers and it is at present contemplated to 10 provide either or both of the novel means of this application on either of the forms of circuit breakers. Similarly, it is contemplated to combine either or both of the novel means of this application with the multi-pole unit of Figs. 19 to 15 28 of that application and with the controlling breakers of Figs. 19 to 30 of that application.

Further, in application Serial No. 667,150, filed April 21, 1933, there is disclosed an automatically operating "Off" holding latch including an electro-magnet, which latch operates automatically to hold the contact arm of the circuit breaker in open position, once that arm has been moved to open position by the circuit breaker mechanism, the holding being continued until the load consuming device has been taken off or cut out of the line. The "Off" holding latch of the application just mentioned may be added as an appendage to any of the devices shown in this application. 25

Further, in application Serial No. 667,152, filed April 21, 1933, there is shown a means for limiting the number of cycles of overload release and automatic reset that can occur before the operator is called upon to reset the device. This auxiliary may be added to any of the breakers 30 35 here shown, if desired.

Further, various combinations of the features here shown and of the features shown in the copending applications just referred to may be effected, and it is the present intention to cover in this application as well as the applications above referred to, combinations of the devices and auxiliaries specifically shown in those applications with any or all of the devices or combinations here shown. 40 45

Now, having described the different forms of breakers, reference will be had to the following claims which determine the scope of the invention, it being expressly understood that the breakers heretofore described and disclosed have been chosen merely as examples, and not as illustrating all of the possible embodiments of the invention. 50

I claim:

1. An automatically releasing and resetting circuit protecting breaker including an enclosing casing, an automatically operating spring means for effecting release and reset cyclic movement of said breaker, and an externally visible indicator 60 automatically moved on release or reset movement of said spring means for indicating the nature of the latest movement of said means, and also for indicating when, if at all, the spring means has had its potential energy reduced to 65 an undesirable extent.

2. An automatically releasing and resetting circuit protecting breaker including an enclosing casing, an automatically operating spring means for effecting release and reset cyclic movement 70 of said breaker, means responsive to the relative strength of said spring means with respect to its original strength for preventing reset movement of said spring means when the latter has had its potential energy reduced to an undesirable 75

extent, and an externally visible indicator automatically moved on release or reset movement of said spring means for indicating the nature of the latest movement of said means, and also 5 for indicating when, if at all, the spring means has had its potential energy reduced to an undesirable extent.

3. An automatically releasing and resetting circuit protecting breaker including an enclosing 10 casing, an automatically operating spring means for effecting release and reset cyclic movement of said breaker, means responsive to the relative strength of said spring means with respect to its original strength for preventing reset movement of said spring means when the latter has had its potential energy reduced to an undesirable extent, and constructed to cause the breaker parts to remain in released position until sufficient potential energy is restored to said 15 spring means, and an externally visible indicator automatically moved on release or reset movement of said spring means for indicating the nature of the latest movement of said means, and also for indicating when, if at all, the spring 20 means has had its potential energy reduced to an undesirable extent.

4. An automatically releasing and resetting circuit protecting breaker including an enclosing 25 casing, an automatically operating spring means for effecting release and reset cyclic movement of said breaker, and an externally visible indicator automatically moved on release or reset movement of said spring means for indicating the nature of the latest movement of said 30 means, and also for indicating when, if at all, the spring means has had its potential energy reduced to an undesirable extent, the indicator having two release positions, one of which indicates merely the fact of release, and the other of which indicates the fact of release, and, in addition, the necessity for restoring potential 35 energy to the spring means, and one reset position which indicates the fact of reset.

5. An automatically releasing and resetting 40 circuit protecting breaker including an enclosing casing, an automatically operating spring means for effecting release and reset cyclic movement of said breaker, means responsive to the relative strength of said spring means with respect to its 45 original strength for preventing reset movement of said spring means when the latter has had its potential energy reduced to an undesirable extent, and constructed to cause the breaker parts to remain in released position until sufficient potential 50 energy is restored to said spring means, and an externally visible indicator automatically moved on release or reset movement of said spring means for indicating the nature of the latest movement of said means, and also for indicating 55 when, if at all, the spring means has had its potential energy reduced to an undesirable extent, the indicator having two release positions, one of which indicates merely the fact of release, and the other of which indicates the fact of release, and, in addition, the necessity for restoring potential 60 energy to the spring means, and one reset position which indicates the fact of reset.

6. In an automatically releasing and resetting 65 circuit protecting device, automatic means for releasing and resetting said device, and means responsive to the relative strength of said automatic means with respect to its original strength for inhibiting resetting operation thereof when the latter has been weakened to a predetermined 70 extent, and for maintaining the device in re-

leased condition, and for indicating not only the fact but also the reason for the device being in such released condition.

7. In an automatically releasing and resetting 5 circuit protecting device, automatic means for releasing and resetting said device and means responsive to the relative strength of said automatic means with respect to its original strength for inhibiting resetting operation thereof when the latter has been weakened to a predetermined 10 extent, and for maintaining the device in released condition, and for indicating not only the fact but also the reason for the device being in such released condition, the inhibiting means being adjustable to vary the amount of weakening of 15 the automatic means necessary to cause the operation of the inhibiting means.

8. In an automatic releasing and resetting circuit breaker, automatic releasing and resetting means, means responsive to the relative strength 20 thereof with respect to its original strength for inhibiting resetting operation thereof when the latter has been weakened to a predetermined extent and for maintaining the breaker released, the inhibiting means being adjustable to vary 25 the amount of weakening of the automatic means necessary to cause the operation of the inhibiting means, and thus to vary the number of cycles of release and reset that will take place before the breaker is maintained released. 30

9. In an automatic releasing and resetting circuit breaker, a spring constantly tending to create cyclic release and reset movement of the parts thereof, and a latch for inhibiting resetting movement of the parts, after cyclic movement had 35 started, said latch being controlled by the relative condition of said spring with respect to its original condition and being rendered operable to inhibit reset when the spring has been sufficiently weakened from the condition it had before 40 the spring started the immediately preceding cycle of release and reset, and manually operable means operable after the latch has been rendered operable for inhibiting reset to release said latch and thereby permit said spring to cause reset. 45

10. In an automatically releasing and resetting circuit protecting device, automatic means for releasing and resetting said device, and means responsive to the relative strength of said automatic means with respect to its original strength 50 for inhibiting resetting operation thereof when the latter has been weakened to a predetermined extent, and for maintaining the device in released condition.

11. In an automatically releasing and resetting 55 circuit protecting device, automatic means for releasing and resetting said device, and constructed to lose strength as it operates, and means responsive to the relative strength of said automatic means with respect to its original strength 60 for inhibiting resetting operation thereof when the latter has been weakened to a predetermined extent, and for maintaining the device in released condition.

12. In an automatically releasing and resetting 65 circuit protecting device, automatic means for releasing and resetting said device, and constructed to lose strength as it operates, and means responsive to the relative strength of said automatic means with respect to its original strength 70 for indicating the fact that said automatic means has lost a predetermined amount of strength, said indicating means also serving to inhibit resetting operation of said automatic means when the lat- 75

ter has lost the predetermined amount of strength.

13. In an automatically releasing and resetting circuit protecting device, automatic means for releasing and resetting said device, and constructed to lose strength as it operates, and means responsive to the relative strength of said automatic means with respect to its original strength for indicating the fact that said automatic means

has lost a predetermined amount of strength, said indicating means also serving to inhibit resetting operation of said automatic means when the latter has lost the predetermined amount of strength and also serving to indicate, when such 5 be the case, that the breaker is held released by the fact that the automatic means thereof has lost the predetermined amount of strength.

WILLIAM H. FRANK.

CERTIFICATE OF CORRECTION.

Patent No. 2,036,266.

April 7, 1936.

WILLIAM H. FRANK.

It is hereby certified that error appears in the printed specification of the above numbered patent requiring correction as follows: Page 2, second column, line 11, for "spring" read frame; and that the said Letters Patent should be read with this correction therein that the same may conform to the record of the case in the Patent Office.

Signed and sealed this 5th day of May, A. D. 1936.

Leslie Frazer

Acting Commissioner of Patents.
